UNITED STATES PATENT OFFICE
2,574,227
SHANK GRIP SLIDABLE JAW WRENCH
Walter Sarvie, Alexandria, Minn.
Application April 28, 1948, Serial No. 23,779
6 Claims. (Cl. 81—152)

1
This invention relates generally to wrenches, and more particularly to a wrench adapted for quick adjustment and for alternative use as pliers and as a clamp.

A primary object of this invention is to provide a combination wrench and pliers, in which the change from a wrench to pliers is made by simply adjusting a set screw.

Another object of this invention is to provide a combination tool of the character mentioned above in which the clamping action may be acquired as a result of a single movement or a succession of movements of a lever pivoted on a movable jaw.

Still another object of this invention is to provide an arrangement of a movable jaw and latch plates on a shank member which may be incorporated in different types of tools such as pipe wrenches, bolt cutters, and many other tools in which one jaw is made to approach another jaw.

And a last object to be specifically mentioned is to provide a wrench having a very positive gripping action, which is safe, simple and very convenient to use, and which will give generally efficient and durable service.

With these objects definitely in view, this invention resides in certain novel features of construction, combination and arrangement of elements and portions as will be hereinafter described in the specification, particularly pointed out in the appended claims, and illustrated in the accompanying drawings which form a material part of this application, and in which:

Figure 1 is a side elevational view of the assembled tool, portions of the tool being broken away and the underlying parts being shown in elevation and in vertical section, in order to amplify the disclosure of the structural details of this tool;

Figure 2 is a horizontal sectional view, taken substantially upon the line 2—2 in Figure 1;

Figure 3 is a similar horizontal sectional view, taken on the line 3—3 in Figure 1;

Figure 4 is a view similar to Figure 1 but illustrating a modified form of this invention in which the part referred to hereinafter as the handle in Figure 1 is deleted and the shank which is integral with the fixed jaw in both Figures 1 and 4 is elongated to comprise a handle for the wrench, and this embodiment of the invention is further simplified by provision of only one latch plate; and

Figure 5 is a similar fragmentary view of a second modified form in which the latch plate is linked to the movable jaw at one end and a dif-

ferent type of spring is used to bias this latch plate into a position in which the latch plate does not grip the shank.

Similar characters of reference designate similar or identical elements and portions throughout the specification and throughout the several views of the drawing.

Referring now to the drawing in detail, this invention includes a tool having a fixed jaw 10 which is preferably integral with a shank 12, a movable jaw 14, a lever 16 and means for releasably fixing the movable jaw on the said shank.

In the preferred embodiment of this invention, illustrated in Figures 1, 2 and 3, which will be described first, a handle 18 is formed integral with the fixed jaw 10 and the shank 12. The shank 12 is preferably rectangular in cross section and the movable jaw 14 is provided with a rectangular transverse aperture so that the movable jaw will slide reasonably freely upon the shank, the working faces 20 of the jaws registering, of course, and a heel portion 22 of the movable jaw extending in the general direction of the handle 18.

A generally U-shaped plate 24 is rigidly secured to the outer side of the movable jaw 14, as indicated at 26, and this plate is apertured to receive the shank 12 and a portion of the lever 16 which is pivoted, as at 28, on the movable jaw 14, and it may be here noted that the pivoted end of the lever 16 is bifurcated with the furcations 30 disposed laterally of the movable jaw 14.

A spring 32, of coil type, is arranged coaxially on the shank 12 and is compressed between the bight portion of the plate 24 and a latch plate 34. This latch plate is apertured to slide over the shank 12, the edges of the aperture being adapted to bite into the shank when the latch plate is disposed at a particular angle therewith, that is, the aperture 36 in the latch plate is formed with at least one pair of parallel sides inclined to the shank 12 when the latch plate is normal thereto, and the spring 32 is adapted to bias the latch plate into a position substantially normal to the shank but so that the latch plate will not grip the shank.

In the embodiment represented in Figure 1, a second spring 38 is provided and a second latch plate 40 is mounted between this second spring 38 and a projection 41 on the outer face of the movable jaw 14. This second latch plate has an aperture 42 similar to the aperture 36 and the plates operate upon a similar principle. The second latch plate has a lip 44 adapted to engage operatively the first-mentioned latch plate 34 on

the side thereof remote from the pivot pin 28 when the second latch plate 40 is forced outwardly by pivotal movement of the lever 16 with its integral furcations 30 and the inturned ears 46 thereon, best illustrated in Figure 2, which engage the second latch plate when the lever is moved substantially normal to the moving jaw 14. It will thus be seen that the ears 46 move the second latch plate into nongripping relation with the shank 12 and continued movement of the lever 16 will cause the latch plate 34 to be also shifted into more accentuated non-gripping relationship with the shank.

Ordinarily, however, this movement of the lever 16 is reversed for disengagement of the wrench from work wherewith it is being used, and disengagement of the first-mentioned latch plate 34 is accomplished by coaction between the springs 32 and 38 acting upon this latch plate when the same is in engagement with the transversely disposed pin 48 carried by the pivoted end of the lever 16. In the position of the elements indicated in Fig. 1, this transversely disposed pin 48 is in a position to press the latch plate 34 into gripping relationship with the shank 12. Obviously, shifting of the lever 16 about its pivot point 28 will move the pin 48 out of engagement with the latch plate 34 immediately after this plate engages the lip 44 and this latch plate is released. The releasing of the latch plate 34 by the pin 48 does not release the latch plate 40, and it will therefore be understood how this construction allows for successive shifting of the lever 16 without the simultaneous release of the second latch plate 40 from the shank, and it will be further understood how a progressive gripping action is accomplished by the tool.

When it is desired to operate this tool as a pair of pliers, a set screw 50, threadedly mounted in the heel 22 of the movable jaw 14, is turned inwardly until the inner end of the set screw engages the second latch plate 40 at a point remote from the transverse pin 48. It will be clear how the set screw 50 will shift this latch plate 40 into non-gripping relationship with the shank, and since the other latch plate 34 is released each time the lever 16 is actuated in one direction, it will be clear how this tool is adapted for use as a pair of pliers by merely screwing the set screw 50 inwardly. An end plate 52 may be secured to the outer end of the shank 12 by a stud 54, to retain the movable jaw and parts carried thereby from separating away from the shank 12.

In the modified form of this invention illustrated in Figure 4, the handle 18 is deleted and the shank 12' is elongated to comprise a handle member. The U-shaped plate 24, spring 32, and latch plate 34, as well as the lever 16 and its pivotal connection 28 on the movable jaw 14, are not changed materially. However, in this modified form, the latch plate 40 is deleted and the transverse pin 48, along with the spring 32, comprise the sole manipulating members for the single latch plate 34.

In the modified form of this invention illustrated in Figure 5, the transverse pin 48 is deleted and the slightly modified latch plate 34' is connected by links 56 with the lever 16, the links being connected to the lever and to the latch plate by pivot pins 58 and 60, respectively. Another end of the modified latch plate 34', disposed on the side of the shank 12' remote from the pivot pin 60, is biased into non-gripping relation with the shank 12' by a modified spring 32' which is carried by a heel portion of the movable jaw

14 and has an end 62 looped around the last-mentioned end of the modified latch plate 34'.

The said heel portion is also analogous, in function, to the ears 46 shown in Figure 1. The coaction between the lever 16 and the plate 34' is functionally analogous to the coaction between the lever 16 and the latch plate 34 already described.

The operation of this invention will be clearly understood from the foregoing description of the mechanical details thereof, taken in connection with the above recitation of the objects sought to be achieved by this invention and a consideration of the drawings. The modified forms described are achieved largely by deletion of elements from the embodiment illustrated in Figures 1, 2 and 3, and the operation of the modified embodiments is similar but necessarily more limited than the operation of the preferred embodiment.

Obviously, many minor variations may be made in the exact construction and the proportionment of the various elements of this invention without departure from the spirit and scope thereof. Accordingly, the scope of this invention should be determined only in accordance with a proper interpretation of the terminology used in the subjoined claims.

Having described the invention, what is claimed as new is:

1. A wrench having a handle with a shank and a fixed jaw thereon, a movable jaw slidably mounted on said shank for coaction with said fixed jaw, a latch plate having an aperture receiving said shank and having a pair of parallel sides terminating in sharp edges to grip said shank when tilted relative to said shank, a spring biasing the latch plate into a second position substantially perpendicular to said shank for easy sliding thereon, and a lever pivoted on said movable jaw and extending in spaced relation to said handle so that said handle and lever can be grasped by hand, said lever having a member rigidly secured thereon and engageable with said latch plate for tilting the same into shank-gripping position.

2. A wrench having a handle with a shank and a fixed jaw thereon, a movable jaw slidably mounted on said shank for coaction with said fixed jaw, a latch plate angularly apertured to receive said shank and having a pair of parallel sides terminating in sharp edges to grip said shank when tilted relative to said shank, a spring biasing the latch plate into a second position substantially perpendicular to said shank for easy sliding thereon, and a lever pivoted on said movable jaw and extending in spaced relation to said handle so that said handle and lever can be grasped by hand, said lever having a member rigidly secured thereon and engageable with said latch plate for tilting the same into shank-gripping position, a plate apertured to receive said shank and secured to said movable jaw, said spring being coaxial with said shank and compressed between said last-mentioned plate and said latch plate.

3. A wrench having a handle with a shank and a fixed jaw thereon, a movable jaw slidably mounted on said shank for coaction with said fixed jaw, a latch plate angularly apertured to receive said shank and having a pair of parallel sides terminating in sharp edges to grip said shank when tilted relative to said shank, a spring biasing the latch plate into a second position substantially perpendicular to said shank for

easy sliding thereon, a lever pivoted on said movable jaw and extending in spaced relation to said handle so that said handle and lever can be grasped by hand, said lever having a member rigidly secured thereon and engageable with said latch plate for tilting the same into shank-gripping position, and means for rendering the said spring and latch plate ineffective so that the wrench may be used in the manner of pliers.

4. A wrench having a handle with a shank and a fixed jaw thereon, a movable jaw slidably mounted on said shank for coaction with said fixed jaw, a latch plate angularly apertured to receive said shank and having a pair of parallel sides terminating in sharp edges to grip said shank when tilted relative to said shank, a spring biasing the latch plate into a second position substantially perpendicular to said shank for easy sliding thereon, a lever pivoted on said movable jaw and extending in spaced relation to said handle so that said handle and lever can be grasped by hand, said lever having a member rigidly secured thereon and engageable with said latch plate for tilting the same into shank-gripping position, and means for rendering the said spring and latch plate ineffective so that the wrench may be used in the manner of pliers, said means comprising an adjustable member on said movable jaw on the side thereof remote from

said member on the lever to prevent the tilting of the latch plate when the movable jaw is in certain positions.

5. A wrench according to claim 1 and wherein said lever has a member rigidly secured thereon and engageable with said latch plate on the side thereof remote from said portion to release said plate from tilted and shank-gripping position when said lever is shifted into one position.

10 6. A wrench according to claim 1 and including a second latch plate on said shank, and a second spring compressed between said latch plates, the one of said plates more nearly adjacent the movable jaw having a member engaging the other 15 of said plates.
